(Cl. D83—12)

FIGURE 1 is a top plan view of a hemostat, showing our new design;

FIGURE 2 is a side elevation thereof, as seen from the right of FIGURE 1;

FIGURE 3 is a bottom plan view thereof;

FIGURE 4 is a side elevation as seen from the right of FIGURE 3;

FIGURE 5 is a sectional view taken along the line 5-5 of FIGURE 1;

FIGURE 6 is a top plan view of a hemostat, showing a modified form of the design of FIGURES 1 through 5;

FIGURE 7 is a side elevation thereof, as seen from the right of FIGURE 6; and

FIGURE 8 is a sectional view taken along the line 8-8 of FIGURE 6.

The dominant features of our design are in the portions shown in full lines.

This is a continuation-in-part of design application Ser. Nos. D. 2,297, filed May 13, 1966 and D. 2,325, filed May 16, 1966 and now abandoned.

We claim:

The ornamental design for a hemostat, substantially as shown and described.
